CLAIM

The ornamental design for a chair with a mesh back as shown and described.

DESCRIPTION

FIG. 1 is a perspective view showing the right side, top and front of a chair with a mesh back which forms my new design;

FIG. 2 is a perspective view showing the left side, top and rear thereof;

FIG. 3 is a front elevational view thereof;

FIG. 4 is a left side elevational view thereof;

FIG. 5 is a rear elevational view thereof;

FIG. 6 is a right side elevational view thereof;

FIG. 7 is a top plan view thereof; and,

FIG. 8 is a bottom plan view thereof.

The broken lines in the figures indicate environment that forms no part of the claimed design.

1 Claim, 7 Drawing Sheets
